UNITED STATES PATENT OFFICE.

JOHN BRUGGER, OF NEW YORK, N. Y.

INTERNAL-COMBUSTION ENGINE.

Application filed January 13, 1927. Serial No. 160,812.

This invention relates to internal combustion engines, and broadly considered has for its primary object and purpose to provide in an engine of this type improved means for transmitting the power impulse of the exploded charge to the crankshaft whereby the dead center and the possibility of back firing is overcome and which will possess greater speed acceleration possibilities than engines 5 of this type now generally employed for the propulsion of motor vehicles and other uses.

It is a more particular object of my invention to provide in each cylinder of the engine two pistons one reciprocating within the 15 other and having opposed heads at one of their ends providing a combustion chamber therebetween in which the charge is exploded to drive said pistons in relatively opposite directions, and power transmitting 20 connections between said pistons and separate crank arms projecting in relatively opposite directions from the crankshaft center and out of radial alignment with each other.

It is also another object of the invention to 25 provide each cylinder of the engine with means whereby air is compressed in the upper end of the engine cylinder in the power stroke of one of the pistons and such compressed air being utilized for forcibly feeding 30 the combustible gas mixture through the intake valve to the combustion chamber.

It is also a further general object of the 35 invention to provide an internal combustion engine of the above character which is relatively simple in construction and arrangement of the mechanical parts thereof so that it will not be liable to get out of order or require frequent repair and may also be produced at comparatively small manufacturing 40 cost.

With the above and other objects in view, the invention consists in the improved internal combustion engine and in the form, construction and relative arrangement of its 45 several parts as will be hereinafter more fully described, illustrated in the accompanying drawings, and subsequently incorporated in the subjoined claims.

In the drawing, wherein I have illustrated 50 one simple and practical embodiment of the invention, and in which similar reference characters designate corresponding parts throughout the several views,—

Figure 1 is a vertical sectional view through one of the cylinders of an internal

combustion engine illustrating one practical embodiment of my present improvements;

Fig. 2 is a sectional view taken on the line 2—2 of Fig. 1, but showing the positions of the relatively movable pistons at the end of 60 the power stroke;

Fig. 3 is a horizontal sectional view taken substantially on the line 3—3 of Fig. 1, and

Fig. 4 is a diagrammatic view illustrating the relative positions of the connecting rods 65 between the pistons and the crankshaft with the pistons in the positions shown in Fig. 2 of the drawing.

Referring in detail to the drawing, 5 designates one of the engine cylinders having 70 its upper portion surrounded by the usual water jacket 6 and fixed at its lower end upon a suitably formed crank case 7. These parts may be all of more or less conventional form, and it will be understood that any 75 desired number of cylinders 5 may be cast en bloc, or in multiple. With each of the cylinders at one side thereof the manifold connection 8 is formed, said connection having an intake passage indicated at 9 and a 80 similar exhaust passage shown at 10 in Fig. 3 of the drawings to which suitable intake and exhaust manifolds respectively, are adapted to be connected. Communication between these passages 9 and 10 and a common 85 port 11 leading to the interior of the cylinder 5 is controlled by the intake and exhaust valves 12 and 13 respectively. As herein shown, these valves are of the usual poppet type normally urged to their closed positions 90 by suitable springs indicated at 14 and operated by the cam shaft 15. It will however, be understood that valves of the rotary sleeve type, or of other constructions as heretofore used in connection with internal combustion 95 engines might be employed.

The upper end of the cylinder 5 is closed by the head 16 having an air inlet passage 17 and an air outlet passage 18 therein. In the outer ends of these passages, suitable 100 valves 19 and 20 respectively are mounted, and preferably an approved type of air cleaner is associated with the inlet valve 19. The air outlet passage 18 is connected preferably by means of a flexible pipe or conduit 105 to the carburetor of the engine whereby pre-heated air under pressure is supplied to the carburetor to effect a more thorough vaporization of the liquid fuel and obtain a forcible feed of the charge through the intake 110

passage 9, as will be hereinafter more fully explained.

Within the cylinder 5, an outer comparatively long tubular piston 21 is slidingly fitted, said piston being provided at spaced intervals in its outer surface with the usual packing rings indicated at 22. At its upper end this piston is provided with the head 23 and at one side of the piston and extending 10 downwardly from this head 23 the longitudinally elongated intake and exhaust port 24 is formed through the wall of the piston and is in registering relation with the port 11 in the cylinder wall.

15 Within the tubular piston 21, a second relatively short piston 25 is reciprocatingly assembled and is likewise provided in its outer surface with the customary packing rings 26. The upper end of this piston is 20 also formed with a head 27. Preferably the opposed surfaces of the piston heads 23 and 27 are concave.

The crankshaft 28 is suitably journalled in bearings provided on the walls of the 25 crank case 7. For each engine cylinder, this shaft is provided with the spaced crank arms 29 projecting in the same direction from the axis of the crankshaft. These crank arms are connected by the spaced connecting rods 30 with a wrist pin 31 extending diametrically through the lower end of the piston 21 and having its opposite ends suitably mounted in the wall of said piston. The intermediate portion of this wrist pin 35 is preferably flattened or of rectangular form as shown at 32.

The spaced crank arms 29 are connected by a third crank 33 which projects from the opposite side of the center of the crankshaft 40 and is out of radial alignment with the cranks 29. Preferably, this crank 33 is offset from the crankshaft center with respect to the cranks 29 about 30°. The crank 33 is connected by a rod 34 with the wrist pin 35 of the inner tubular piston 25. This connecting rod 34 has a longitudinally extending opening in its intermediate portion through which the flattened central part 32 of the wrist pin 31 extends, and permits of 50 the angular movement of said connecting rod 34 relative to said wrist pin.

As shown in Fig. 1 of the drawings, the two pistons 21 and 25 have compressed the charge admitted through the intake valve 55 12 and through the port 11 between their opposed heads 23 and 27 and the crank 33 of the shaft 28 is approximately at the upper dead center position while the cranks 29 have passed the lower dead center position on 60 their upward movement, at the left thereof as indicated by the arrow in the drawing. When the circuit of the spark plug shown at 36 is now closed through the ignition system, the compressed gas is ignited and the 65 pressure of the exploded charge is exerted

substantially equally in opposite directions against the opposed piston heads 23 and 27 so that the outer piston is moved upwardly while the inner piston is moved downwardly. This results in the continued upward movement of the cranks 29, thereby moving the crank 33 beyond the dead center position shown in Fig. 1. It will therefore, be apparent that it is impossible for the explosion to take place before the crank 33 has reached 70 the dead center position and that owing to the relative angular arrangement of the cranks 29 and 33, the thrust of one or the other of the pistons will be transmitted to the crankshaft in angular relation to the upper or lower dead center positions.

In Fig. 4 of the drawings, I have shown the pistons at the end of the power stroke and the cranks 29 and 33 therefor in the opposite relation to the crankshaft center 85 from that shown in Fig. 1. From reference thereto, it will be observed that the connection of the rod 34 of the inner piston with the crank 33 is now approximately at the lower dead center position while the 90 crank connections 29 to the outer piston are disposed at the right of the upper dead center position.

It will also be noted that by the provision of the two pistons reciprocating in relatively 95 opposite directions to transmit the power impulse to the crankshaft, I am enabled to shorten the piston stroke and correspondingly shorten the length of the cranks and reduce the angular movement of the connecting rods 30 and 34. Thus, better acceleration from the lower to the higher 100 speeds is possible than can be obtained in the use of the usual single piston in each cylinder.

After the power stroke, in the following upward movement of the inner piston and the downward movement of the outer piston, the burned gases are expelled, it being understood that the exhaust valve 13 is open during the initial part of this movement of the pistons. As the pistons again approach the position as seen in Fig. 1, the exhaust valve closes and the intake valve is opened so that 110 a fresh charge is admitted to the combustion space between the piston heads. Thereafter 115 the charge is exploded and the above described cycle is repeated.

In the downward movement of the outer piston to the position of Fig. 1, air is drawn 120 into the upper end of the cylinder 5 through the valve 19, and in the subsequent upward power stroke of this outer piston, the air is compressed in the upper end of said cylinder until the spring-held valve 20 is 125 overcome, when the air is expelled under pressure through the conduit connection to the carburetor. Since the wall of the cylinder 5 becomes more or less highly heated from the exploded gases, it is apparent 130

that this air which is compressed in the upper end of the cylinder will absorb a certain proportion of such heat. Therefore as heretofore explained, such preheated compressed air admitted to the carburetor will produce better vaporization of the liquid fuel and likewise constitute means for conveying the vaporized fuel under pressure to port 11 as well as furnishing the desired volume of oxygen for insuring proper combustion of the mixture.

From the foregoing description considered in connection with the accompanying drawing, it will be seen that I have devised a very simple and novel type of internal combustion engine whereby the dead center position of the crankshaft is effectively overcome and the possibility of back firing due to pre-ignition of the combustible charge is obviated. Also, due to the transmission of the thrust to the crankshaft by pistons moving in relatively opposite directions and thereby shortening the stroke, greater freedom from vibration and acceleration of the speed more quickly than has heretofore been possible may be realized. It will also be noted that the construction and arrangement of the two pistons and their connections with the crankshaft are of relatively simple mechanical form so that they will function in a positive and reliable manner and are not subject to excessive strain or likely to require more or less frequent repair.

I have herein shown a practical embodiment of my present improvements which I believe to be best adapted for the intended purpose, but it will nevertheless be understood that the essential features thereof are also susceptible of embodiment in various other alternative structural forms, and I accordingly reserve the privilege of resorting to all such legitimate changes in the form, construction and relative arrangement of the various detail parts as may be fairly embodied within the spirit and scope of the invention as claimed.

I claim:

1. In an internal combustion engine, a

cylinder, two pistons in said cylinder reciprocating one within the other and having spaced heads forming a combustion chamber therebetween, a power shaft having spaced cranks projecting from one side of its axis and a third crank between said spaced cranks projecting upon the opposite side of the shaft axis and out of radial alignment with said first named cranks, a pair of rods connected at one of their ends with said first named cranks, a wrist pin connection between the other ends of said rods and the lower end of the outer piston, a relatively long rod directly connected at one end with said last named crank, and a wrist pin connecting the other end of said latter rod with the inner piston, said wrist pins being located in intersecting relation to the central axial line of the pistons, and said latter rod having a longitudinally extending opening accommodating the first named wrist pin to permit of the relative angular movement of said connecting rod.

2. In an internal combustion engine, a cylinder, two pistons in said cylinder reciprocating one within the other and having opposed heads forming a combustion chamber therebetween, a power shaft having a pair of cranks projecting from one side of its axis and a third crank projecting upon the opposite side of the shaft axis, a single connecting rod directly connecting the latter crank with the inner piston, a pair of connecting rods respectively connected at one of their ends with the first named cranks and having their other ends positioned within the lower end of the outer piston, a wrist pin connecting said ends of the latter connecting rods with the outer piston and extending diametrically across said piston, and the connecting rod between the inner piston and the shaft crank being provided with means positioned with respect to said wrist pin to permit of the angular movement of said connecting rod relative thereto.

In testimony that I claim the foregoing as my invention, I have signed my name hereto.

JOHN BRUGGER.
